UNITED STATES PATENT OFFICE.

JOSEPH S. JONES, OF SPOKANE, WASHINGTON, ASSIGNOR OF ONE-FOURTH TO CHRISTOPHER NAPOLEON ADDLEY, OF SPOKANE, WASHINGTON.

ALARM.

No. 919,179.

Specification of Letters Patent. Patented April 20, 1909.

Application filed October 16, 1907, Serial No. 397,626. Renewed December 28, 1908. Serial No. 469,662.

To all whom it may concern:

Be it known that I, JOSEPH S. JONES, a citizen of the United States, residing at Spokane, in the county of Spokane and State of Washington, have invented a new and useful Alarm; and I do hereby declare the following to be a full, clear, and exact description of the invention, such as will enable others skilled in the art to which it appertains to make and use the same.

This invention pertains to a new and useful alarm device, and in its broadest aspect the invention provides a device of this character especially adapted in case of fire, that is to say, supposing a building equipped with a device of this design should catch afire or any other structure in which it may be desirable to install an alarm device, it would cause a bell in the building or structure to ring about five minutes or more, and it would also cause an electric bell to notify the fire department. The above is accomplished by severing or destroying a cord controlling the bell and a movable contact in the building or structure; this movable contact controls the circuit of the electric bell, as will be further manifest.

This invention comprises further objects and combinations of elements which will be hereinafter more fully described, shown in the accompanying drawings, and the novel features thereof will be pointed out by the appended claims.

To obtain a full and correct understanding of the details of construction, combination of features, elements and advantages, reference is to be had to the hereinafter set forth description and the accompanying drawings in connection therewith, wherein the invention is illustrated in a single view, showing the wiring for the device, and its principal features.

Making renewed reference to the accompanying drawings, wherein similar reference characters indicate corresponding parts in the illustration, by figures, 1 designates the usual form of a spring controlled alarm bell, which is provided with a lever 2, held against the tension of a spring (not shown) within the bell, by means of the cord or cable 3 or similar means, which engages and moves over a plurality of pulleys 4, suitably arranged within a building or other structure so that in case of fire the cord will be severed, thus releasing the lever 2, which will cause the bell to ring until run down, as will be un-

derstood. This cord is secured to an eye 5 forming an integral part of a handle 6 which is integral with the end 7 of the movable contact 8 as further shown; this movable contact is in the form of a shaft, and is mounted in a bearing 9, and is provided with a collar 10, between which and the said bearing 9 a spring 11 is disposed, which has a tendency to force the said contact outward, so as to cause a contact with a stationary contact 12, that is when the said cord 3 is severed by fire. This contact is insulated as at 13 which is extended as at 14 to form a bearing for the end of the movable contact 8, as further shown. The said stationary contact is provided with a binding screw 15 by which the lead 16 is connected thereto, which lead 16 is connected to the binding post 17 of the electric bell 18, as further shown; the lead 16 is provided with a battery 19 which provides current for the apparatus.

Disposed within the handle, which is of an arched shaped design, is a binding screw 20, by which the lead 21 is held to the end 7 of the movable contact 8, as clearly shown in the drawings. This lead 21 is also connected to a binding post 22 of the electric bell 18, as shown. It will thus be seen, when the cord 3 is severed, the movable contact and the lever 2 of the bell 1 is released, thereby causing the bell 1 to ring and closing the circuit of the electric bell; the bell 1 notifies the occupants of the building, and the electric bell 18 is designed to notify the fire department, by the severing of the cord 3.

It is to be understood that various changes and modifications may be employed in the construction and embodiment thereof, combination of features, and elements, without in any way departing from the spirit and scope of the invention covered by the claims thereof; it being understood that whatever variations or modifications are employed must fall within the scope of the appended claims.

From the foregoing, the essential features, elements and the operation of the device, together with the simplicity thereof, will be clearly apparent.

Having thus fully described the invention, what is claimed as new and useful, by the protection of Letters Patent is:—

1. A device of the character described, comprising a stationary contact having a

tubular metal member and a corresponding insulating member receiving said metal member, a movable contact of rod-formation extending into and slidably in said insulating member, a resilient member adapted to deliver its tension or stress upon said slidable or movable contact, means for producing an alarm, said movable contact being provided with a fixed handle of bail-like formation and connecting means between said handle and said alarm producing means, adapted to be readily severed or destroyed by the action of a fire.

2. In a device as set forth, a stationary contact having a hollow bore a portion of which is formed of insulating material, a movable spring-actuated contact received thereby, said movable contact having an

arched shaped handle, an eye integral therewith, an alarm bell having a spring actuated lever, means designed to engage pulleys, one end of which being connected to said lever, while the other end is connected to said eye, said means designed to control said bell and the movable contact, and when severed, said bell and contact being released, an electric bell and battery in circuit with the stationary and movable contacts.

In testimony whereof I have signed my name to this specification in the presence of 39 two subscribing witnesses.

JOSEPH S. JONES.
